UNITED STATES PATENT OFFICE.

ALBERT EDWARD HODGSON AND NORMAN CLARKE JONES, OF LONDON, ENGLAND.

DETACHABLE CYLINDER HEAD FOR INTERNAL-COMBUSTION ENGINES.

Application filed March 26, 1928, Serial No. 264,872, and in Great Britain April 4, 1927.

The use of producer gas for automobile traction, transport purposes and stationary power purposes, is well known and it frequently happens that the employment of this fuel with the ordinary engine designed for use with petrol or paraffin results in considerable loss of power owing to the comparatively low compression of the gas.

It is equally well known that to satisfactorily employ producer gas for this purpose, a considerably increased compression of gas mixture must be available if the power obtained from the engine is to be anything approximating that of an engine when using petrol or paraffin (kerosene).

The object of the present invention is to so construct a detachable cylinder head that the cubic capacity of the space or combustion chamber is materially reduced and so obtain higher ratios of compression than is possible or practicable owing to preignition with the ordinary detachable cylinder head as used with the petrol or paraffin driven motor.

According to the present invention presuming the conversion of the petrol driven motor to the producer gas driven motor and the adaptation thereof to what is known as the L-headed engine wherein admission and exhaust valves are situated on the one side of the cylinder, the detachable head is constructed with a hollow interior as is usual for the petrol motor leaving a sufficient space on the one side within which the valves operate. From this side the cover or head is inclined towards and across the upper side of the cylinder so that a comparatively small space is left between the top of the piston and the under-side of the cover at the remote side of the cover to that enclosing the aforesaid valves thus reducing the cubic capacity of the space beneath the head or cover from 50-75% of that usually employed whereby a very much higher ratio of compression is obtained.

It may be observed in connection with the ordinary internal combustion engine using petrol, paraffin (kerosene) or the like as the fuel supply detachable cylinder heads with domed and sloping interior roofs or cavities provided therein above the valve and pistons are well known for establishing the combustion chamber at the head of the cylinder and creating a turbulence chamber for the explosive mixture with a view to preventing preignition but with the use of producer gas there is no need for the provision of such

definitely formed turbulence chambers as the chance of preignition is not so great and furthermore due to the higher ratio of compression required it becomes practically impossible to provide such turbulence chambers owing to the reduction of the cubic capacity of the compression space or combustion chamber.

Examples of construction embodying the invention are illustrated in the annexed drawings to which reference will now be made in which:—

Figure 1 is a sectional elevation of the ordinary L-headed petrol engine with the admission and exhaust valves situated on one side of the cylinder with our invention applied thereto.

Figure 2 is a fragmentary plan of the under-side of the head or cover shown in Figure 1 and

Figure 3 a cross section of Figure 2.

Figure 4 is a sectional view of a cylinder head or cover of a modified form of construction.

Similar letters of reference relate to the like parts in all the figures of the drawings.

Referring now to the drawings and particularly to Figures 1 to 3 *a* is the cylinder to which is attached the detachable head or cover *b* which is constructed so as to provide the interior chamber *c*. The chamber *c* is so arranged that the engine inlet and exhaust valves *d* and *e* operate within it and the depth of the side or wall *f* of the chamber *c* at the point where the valves operate is so calculated that just sufficient space is available for the valves to open fully. The upper surface or roof *g* of the chamber *c* inclines towards and across the cylinder *a* so that there is a comparatively small space at the opposite side *h* between the top of the piston *i* and the under-side of the roof *g*. The inclination of the roof surface may, however, be more rapid than shown in Figure 1 by forming the same in two or more stages *g*, *g'* successively as shown in Figure 4, inclining from the side *f* to the top of the comparatively non-existent side *h*. In the cross-section Figure 3 the roof surface *g* of the chamber *c* is shown flat or straight but obviously it may be curved or domed, and referring to that illustrated in Figure 4 the portion of the chamber *c* over the valves may be flat and the portion over the piston inclined or triangular as shown in dotted lines, Figure 3.

The sparking plugs used with the detachable cylinder head may be situated in the cavity *k* near the exhaust or inlet valves or directly over the pistons if required or at any convenient point within the compression space inserted from the exterior as usual.

What we claim is:—

In an internal combustion engine, the combination with a body portion comprising cylinder and valve sections and having a flat end with a cylinder opening and a valve opening therein all in the same plane, of a hollow cylinder head of a form to fit said

body portion adapted to be removably connected therewith and presenting the interior roof plate inclined downwardly in stepped form from the valve side to the cylinder side of the engine, the height of the combustion chamber decreasing over the cylinder portion of the combustion chamber toward the side thereof from a line extending from the mid point between the valves and through the piston center.

In testimony whereof we affix our signatures.

ALBERT EDWARD HODGSON.
NORMAN CLARKE JONES.
